(No Model.)

J. T. O'BRIEN.

SECTIONAL LADDER.

No. 300,631.

Patented June 17, 1884.

UNITED STATES PATENT OFFICE.

JOHN T. O'BRIEN, OF PHILADELPHIA, PENNSYLVANIA.

SECTIONAL LADDER.

SPECIFICATION forming part of Letters Patent No. 300,631, dated June 17, 1884.

Application filed May 12, 1884. (No model.)

To all whom it may concern:

Be it known that I, JOHN T. O'BRIEN, of the city and county of Philadelphia, in the State of Pennsylvania, have invented certain new and useful Improvements in Sectional Ladders, whereof the following is a specification, reference being had to the accompanying drawings.

In these, Figure 1 is a front view, partly in elevation and partly in longitudinal section, of a ladder embodying my invention, showing two of the lengths or sectional parts coupled together. Fig. 2 is a side elevation of the same. Fig. 3 is a side elevation of a scaffolding formed by the use of two pairs of the sectional ladders arranged as supports. Fig. 4 is a side view, on an enlarged scale, of the upper ends of the said pair when arranged as such supports; and Fig. 5 is a side view of one of the braces by which the lengths are united.

The object of my invention is to provide a ready means of uniting the pieces of a sectional ladder, so as to permit the extension of such ladder to any desired length, and to enable the said pieces to be used in pairs standing alone like an ordinary step-ladder, the uniting and detaching of the parts being effected in a rapid manner and without the use of cumbersome splicing devices such as have heretofore been generally employed.

In the accompanying drawings each section of the ladder is shown as made up of side pieces or uprights, A A, and cross-pieces or "rungs" B B, which are constructed in the ordinary manner, except in the particulars hereinafter mentioned. The upper end of each upright A is provided with a metal tip, C, formed, as shown, with a horizontal shoulder, a, and a projecting tongue, c, through which tongue a transverse hole, d, is made. The lower end of each upright is also constructed with a metal cap, D, having a central recess or socket, g, (shown in dotted lines,) conforming in shape and size to the tongue c. A transverse hole, f, is formed through the cap D at such a point that when the tongue c of the next upright A in the series is placed home in the socket g, the holes f will register evenly with the hole d of the tongue. At some distance from each end of the upright A, I form transverse holes e, which should be bushed or faced with metal, as indicated. I prefer to use malleable iron for constructing

the various metallic parts referred to. Flat stay-bars E, preferably of wrought-iron, are pierced with holes h, which, when the bar E is placed in the position indicated in Figs. 1 and 2, will register with the holes e of the uprights and the continuous holes d f of the combined tips. Bolts I, having nuts i, are arranged to pass through the series of holes, and thus to clamp the stay-bars E firmly against the uprights A A, so that when combined as shown in Figs. 1 and 2, with the stay-bars E on the outside of each upright overlapping the joints between the sections of the ladder, and the bolts passing through and locking the tongue c into the sockets g, the sections are firmly secured together to form a continuous ladder.

It will be seen that the uniting and disconnection of the sectional parts can thus be accomplished with great ease and rapidity.

In order to enable the sections to be used as an ordinary step-ladder or as supports for a scaffolding, I provide near the upper end of one upright A a stout latch, k, and at a similar distance from the end of an upright of another section a socket, m, adapted to receive and hold the latch, as shown in Fig. 4. The stay-bars E being arranged diagonally, as indicated in Fig. 3, and secured by the bolts I, the pair of sections will be locked in an inclined position, so as to be self-supporting; and if it is desired to form a scaffold two pairs are used, with the scaffold-board G mounted between them.

Having thus described my invention, what I claim as new, and desire to secure by Letters Patent, is—

In a sectional ladder, the combination, with the uprights A A, of the tips C C, arranged thereon at one end of each section, and having tongues c, the caps D D, arranged at the other end of each section, and provided with sockets g, adapted to receive said tongues, the transverse holes d f, formed in said tongues and caps, respectively, and holes e e, formed in the uprights A A, and the stay-bars E, having bolts which pass through said holes, the whole arranged and operating substantially in the manner set forth.

JOHN T. O'BRIEN.
